CLAIM

The ornamental design for a food container, having the shape and configuration as shown and described.

DESCRIPTION

FIG. 1 is a top perspective view of a first embodiment of a food container.

FIG. 2 is a front elevation view of the food container of FIG. 1.

FIG. 3 is a rear elevation view of the food container of FIG. 1.

FIG. 4 is a left side elevation view of the food container of FIG. 1.

FIG. 5 is right side elevation view of the food container of FIG. 1.

FIG. 6 is a top plan view of the food container of FIG. 1.

FIG. 7 is a bottom plan view of the food container of FIG. 1; and,

FIG. 8 is a top perspective view of the food container of FIG. 1, showing the handle in an alternate position of use. The evenly dotted broken lines represent portions of the structure that forms no part of the claim. The dash-dot-dot-dash boundary lines represent boundaries of the claim and form no part of the claim. The dash-dot-dot broken line represents a symbolic break along the height of the container with the dash-dot-dot lines and the space between the break forming no part of the claim.

1 Claim, 6 Drawing Sheets
